CLAIM

The ornamental design for a medical product case holder, as shown and described.

DESCRIPTION

FIG. 1 is a perspective view of a medical product case holder showing the new design in its environment;

FIG. 2 is a perspective view of the medical product case holder;

FIG. 3 is a front elevational view of the medical product case holder of FIG. 2;

FIG. 4 is a rear elevational view of the medical product case holder of FIG. 2;

FIG. 5 is a right side elevational view of the medical product case holder of FIG. 2, the left side thereof being a mirror image;

FIG. 6 is a top plan view of the medical product case holder of FIG. 2; and,

FIG. 7 is a bottom plan view of the medical product case holder of FIG. 2.

The broken lines illustrate environmental subject matter that form no part of the claimed design.

1 Claim, 5 Drawing Sheets
